UNITED STATES PATENT OFFICE

2,526,813

AUTOMATIC ADJUSTABLE WAISTBAND

Ralph R. Fanning, Celina, Ohio, assignor to
Winner, Inc., Berne, Ind., a corporation of Indiana

Application November 20, 1947, Serial No. 787,053

4 Claims. (Cl. 2—237)

1

This invention relates to improvements in garments, and more particularly to a waistband for trousers and like garments that are automatically adjustable in size to the waist of the wearer.

The object of the invention is to provide an automatically adjustable waistband for garments, of simple and economical construction, which is automatically adjusted to the waist of the wearer.

Another object of the invention is to provide an automatically adjustable waistband for garments which conceals the point of adjustment within a plait formed in the side of the garment.

A further object of the invention is to provide an automatically adjustable waistband for trousers which conceals the point of adjustment within side pockets in such a way as to afford side pockets of normal proportions and construction, thus avoiding unsightly wrinkles and gatherings.

Another object of the invention is to provide a waistband that adjusts itself without the use of buckles, clasps and the like, to the waist of the wearer.

A further object of the invention is to provide an automatically adjustable waistband that may be attached to existing styles of trousers.

A further object of the invention is to provide an automatic adjustable waistband for trousers that permits the elimination of the use of a belt and suspenders as well as belt loops and tunnel loops.

A further object of the invention is to provide an automatically adjustable waistband that always presents a neat and close fit about the waist.

Another object of the invention is to provide an adjustable waistband that is automatically extensible and contractible within the locus of the waistband to fit the waist of the wearer.

A further object of the invention is to provide an adjustable waistband that is automatically extensible and contractible within a wide range of adjustments to fit the waist of the wearer in all sitting, bending, lying and standing positions.

A still further object of the invention is to provide an automatically adjustable waistband having sufficiently wide forward elastic elements which will distribute the tension applied over the abdomen in such a way as to render proper abdominal support, thereby replacing separate abdominal support devices where their need is indicated.

In the accompanying drawing forming a part of this specification and in which like numerals are employed to designate like parts throughout the same;

Figure 1 is a perspective view of a pair of

2

trousers fabricated with the automatic adjustable waistband and showing the hidden outline of the left-hand side pocket and the four elastic elements of the automatically adjustable waistband in accordance with my invention.

Figure 2 is a rear elevational view of the trousers shown in Figure 1 with a portion of the right-hand long belt loop broken away to show the attachment of the rear right-hand elastic element.

Figure 3 is an elevational view on an enlarged scale of the left-hand half and an adjacent rear portion of the right-hand half of the trousers of Figure 1 as they would appear in a flat and retracted position. A portion of the left-hand long belt loop is broken away to show the left-hand rear elastic element in retracted positions.

Figure 4 is a view similar to that of Figure 3 but showing the waistband and the side pocket in extended position.

Figure 5 is a view of the garment shown in Figure 3 as viewed from the inside of the trousers.

Figure 6 is a view of Figure 5 with the garment in extended position.

Figure 7 is an enlarged plan view of the top edge of the waistband and trousers shown in Figure 3 with the rear portion broken away.

Figure 8 is an elevational view, similar to Figure 3, of a modified form of the automatically adjustable waistband.

Figure 9 is a view similar to that of Figure 8, but showing the waistband and the side pocket in extended position.

Figure 10 is a view of the modified form shown in Figure 8 as viewed from the inside of the garment.

Figure 11 is a sectional view along the section line 11—11 of Figure 10.

Figure 12 is a view of Figure 10 with the garment in extended position, and

Figure 13 is an elevational view showing an alternative way of attaching an end of an elastic to the waistband lining by means of forming a plait in the lining.

The trousers are fabricated with the usual legs

45 to each having a front panel 11 and a rear panel 12. The rear panel 12 is shown in Figure 1 having a forward extending flap or facing 12a sewn thereto along a seam indicated at 13 while the forward portion of the flap extends underneath 50 the front panel 11. The rear edge or front pocket welt 14 of the front panel 11 tapers rearwardly from top to bottom forming the outer edge of a side pocket and has its bottom portion attached to the rear panel 12 by a tack 15.

55 The upper edge of the front panel 11 has sewn

thereto a front waistband 16 which has a rearwardly extending end or flap 16a as shown in Figures 1, 3 and 4. This front waistband 16 has a facing or curtain 17, see Figure 7, stitched on its back side to its upper and lower longitudinal edges throughout its entire length thereby forming a tubular casing with the front waistband and giving the front waistband more body. Into the rear end of the tubular waistband portion 16a there extends the front end of a rear elastic element 18 which is secured to the tubular portion 16a by stitching 19, while the rear end of the elastic element 18 is made fast by stitching 20 to a rear waistband or flap indicated at 21, to be described later. In the position of the parts shown in Figure 3, the rear elastic element 18 rests in retracted position, while in Figure 4 an extended position of the parts is illustrated wherein the rear elastic element 18 is extended and the front panel 11 and the flap 12a have moved apart relative to each other. The extension of the waistband parts relative to each other is automatic in that they position themselves through the elastic elements so that the waistband fits the waist of the wearer in all positions including standing, bending and sitting.

The rear waistband 21 is formed by the upper portion of the rear panel 12 and the upper portion of the forwardly extending flap portion 12a, both of which extend upwardly to the marginal edge indicated at 22 in Figures 3 to 6. A rear waistband facing or curtain 23 is stitched to the back side of the waistband 21 throughout its entire length by the stitching 24 and 25, see Figure 5, thereby forming a tubular casing with the rear waistband 21. As an alternative fabrication, this rear tubular waistband may be made as a separate tubular element which would then be joined to the rear panel 12 and flap 12a by a stitching similar to that shown at 24. In case this alternative construction is used, the upper marginal edge of the rear panel 12 and flap or facing 12a would lie just above the stitching 24.

A tunnel belt loop or casing 26, extending substantially the width of the rear panel 12, has its upper edge 26a, see Figure 5, extending downwardly between the upper portions of the rear waistband 21 and the rear waistband facing 23 and is secured therebetween by the stitching 25. This belt loop or casing 26 extends outwardly from the waistband and downwardly over the rearwardly extending portion 16a of the front waistband and the rear elastic element 18, see Figures 3 and 4, and has its bottom edge stitched to the rear panel 12 by stitching indicated at 26b in Figures 3 and 4.

The tunnel belt loop 26 is made with sufficient fullness that it permits the customary pants belt to be inserted within the loop and also allows the rearwardly extending front waistband portion 16a and the rear elastic element 18 to slide therein as shown in Figures 3, 4 and 7, thereby concealing the working mechanism of the rear elastic element. The tunnel belt loop 26 is shown in Figures 3 and 4 with its forward end 26c and its rear end 26d tapered downwardly towards each other. Two of the customary belt loops as indicated at 27 in Figures 3 and 4 are secured to the forward waistband 16 and with the tunnel belt loop 26 form a housing for the usual pants belt.

Referring now to Figures 5, 6 and 7, the forward end of the tubular casing formed by the rear waistband 21 and its facing 23 are supported by a forward elastic element 28 which has its rear end portion extending in between the por-

tions 21 and 23 and is secured thereto by stitching indicated at 29. The forward end of this forward elastic element 28 is made fast to the front waistband 16 and its facing 17 towards its forward end by stitching as indicated at 30, thereby leaving the elastic element 28 free to move within the tubular casing formed by walls 21 and 23. An alternative way of attaching the forward end of this elastic element 28 to the waistband curtain or facing 17 is shown in Figure 13, wherein a specially prepared plait would be formed in the curtain for insertion of the end of the elastic element which would be secured in the plait as by stitching.

In cases where more abdominal support is desired, the forward elastic element would be made wider at its forward end which would, in addition to being stitched at the forward waistband 16 as at 30, also be secured to the front panel 11 by the seam, such as indicated at 30' in Figures 1, 4, 5 and 6. This wider forward elastic element would distribute the tension applied over the abdomen in such a way as to provide for proper abdominal support and as such could be used to replace separate abdominal supports where their need is indicated.

A customary button hole 31 is worked into the forward end of the front waistband portion 16. A button 32, as shown in Figure 1, is secured to the forward end of the opposite front waistband 16 of the trousers and cooperates with the buttonhole 31 to hold together the overlapping end portions of the front waistbands 16. Any other suitable fasteners may be substituted for the button and buttonhole fastening here shown.

A customary fly or front opening is indicated at 33 in Figure 1. Any suitable fastening means may be used for closing the garment at the fly. In cases where the automatically adjustable waistband is fabricated in garments as women's slacks, for example, or other such garments where there is no fly or front opening, there is enough expansion or give in the automatically adjustable waistband for the wearer to get into and out of such garments.

A side pocket generally indicated at 34 which is of normal proportions and construction comprises an outer wall 35 and an inner wall 36 which are joined together at their forward edges to form an open plait or foldable portion as indicated at 37. In its most forward position, the forward edge of the open plait is indicated at 38 in Figures 1, 3, 5 and 7, while in its most rearward position, the forward edge of the open plait is indicated at 38' in Figures 4 and 6. Thus, it will be seen that the forwardly extending foldable portion 37 of the pocket constitutes a surplus unattached portion so that the outer wall 35 of the pocket, which is connected to the front panel 11, is displaced upon expansion of the forward elastic element 28. On the other hand, the inner wall 36, which is connected to the rear panel 12, is displaceable upon longitudinal movement of the rear elastic element 18. By reason of this arrangement of parts, the double elastic members work against each other automatically to adjust the front and rear panels to snugly fit the user and insure a smooth, even, and neat appearance to the waistband by avoiding unsightly wrinkles and gathering of the garment. The rearward portion of the upper edge 39 of the outer wall 35, see Figures 3 and 6, is attached to the lower and adjacent edge of the front waistband 16 leaving the forward portion of the upper edge of the outer wall unsecured so as to form a

portion of the open plait 37. The rear edge of the outer wall 35 is stitched to the rear edge 14 of the front panel 11 as by stitching indicated at 40 in Figures 1, 3 and 4, thereby forming the front pocket welt. The inner wall 36 has the rearward portion of its upper edge 41, see Figures 5 and 6, stitched to the lower adjacent edge of the forward end of the rear waistband 21 by the stitching indicated at 24. The rear edge of the inner wall 36 which lies behind the flap portion 12a is secured at the seam 13 which secures the rear edge of the flap 12a and the front edge of the rear panel 12 as shown in Figures 3 to 6. The front edge of the flap 12a along the line at 42 is also sewn to the rear wall 36 of the pocket. The front wall 35 and the rear wall 36 of the pocket 34 are joined together at their lower and rear edges indicated at 13a, see Fig. 1, below the pocket opening and are allowed to swing free of the side seam 13 to form a side swing pocket.

The waistband expands through the elastic elements 18 and 28 to a size to accommodate the waist of the wearer. This is accomplished automatically as the garment is worn with the two front waistband portions 16 brought together and secured in position relative to each other as by the button 32 and the buttonhole 31. In cases where the front of the garment is continuous as in women's slacks, or other such garments where there is no fly or front opening, the elastic elements 18 and 28 permit automatic expansion as well as adjustment to allow for putting on and taking off such garments.

The rear elastic elements 18 and the forward elastic elements 28 are totally concealed from view when observing the waistband from the outside thereof. These elastic elements work against or in opposition to each other in holding the various parts of the formfitting waistband and waist portion of the garment so as to permit their automatic adjustment to the waist of the wearer, and at the same time, effect a smooth, even appearance.

The elastic elements of the automatically adjustable waistband above described and the modified form of waistband, later described, may be of various types of elastic material in various widths, strengths and character to supply the proper tension and body to meet the requirements of keeping the garment snugly adjusted to the waist of the wearer and to give the proper tension to support the garment. Further, the automatically adjustable waistband provides for proper abdominal support especially when the forward elastic element is made wider as has been previously pointed out. The automatically adjustable waistband permits a wide range of adjustments at the waist of the wearer as is required when in various positions of sitting, bending, lying and standing.

The flap or facing 12a attached to the rear hip panel 12 lies underneath or behind the front hip panel 11. The expansion and contraction of the automatically adjustable waistband causes the flap 12a and rear hip panel 12 to move relative to the front hip panel 11 of the garment. By having the walls of the side pockets, through the area of the side pocket opening, attached respectively to these hip panels of the garment and with a portion of the top edges of the walls of the pockets attached to the front and rear waistbands, any adjustment of the waistband and the hip panels is taken up in the adjustment of the walls of the side pockets. By referring

to Figures 1 and 3 through 6, there is best illustrated the action of the side pocket walls 35 and 36 relative to each other, wherein a somewhat swinging and sliding action of the inside pocket wall 36 takes place relative to the outside pocket wall 35. The pocket as here described and the overlying portion of the front panel 11 and the rear panel flap 12a serves the function of an open plait, wherein adjustment is concealed. In cases of ladies' garments, such as skirts and slacks, an open plait within which adjustment would be concealed would replace such a pocket. The side walls of pockets could be omitted and the overlying portions of the front panel and the rear panel flap would serve as an open plait within which adjustment at the waistband would be concealed.

A modified form of the automatically adjustable waistband shown in Figures 8 through 12 and its attachment to trousers will now be described. The modified form does not require the regular belt and tunnel loops. In Figure 8, the front panel is indicated at 50, while the rear panel is indicated at 51. The rear panel extends forward to a seam 52 by which it is attached to a forward extending flap or pocket facing 51a extending forward to where its forward edge 53 is attached to the adjacent inner wall of the side pocket by stitching 53', see Figures 8 to 12. The flap portion 51a, as will be seen in Figures 8 and 9, lies behind the outer wall of the side pocket to be described later. The seam joining the rear panel 51 and the flap portion 51a extends upward to a point indicated at a in Figures 8 and 9 thereby leaving unattached the forward upper portion of the rear panel extending between points a and b.

A rearwardly extending waistband portion 54 has its forward end attached to the front panel 50 by a seam at 55 from which it extends rearwardly behind the rear panel, as shown at point a to point b and by the broken away portion of the rear panel 51 in Figures 8 and 9. A facing or curtain piece 56, Figures 10 and 12, has its upper edge secured to the upper edge of the front panel 50, while its forward edge is sewn to the adjacent fly or opening portion of the front panel. The portion along the rear edge of the curtain 56 overlies the front end of a second facing or curtain piece 57 which has its upper edge portion secured to the upper edge portion of the adjacent front panel and the rearwardly extending waistband portion 54. The facing pieces 56 and 57 and the waistband portion 54 forms what is termed the front waistband. Where the facing 57 extends behind the back side of the waistband portion 54, the lower edge is also stitched to the waistband portion and forms therewith a tubular casing indicated generally at 58 in Figures 8 and 9. The lower edge of the facing or curtain pieces 56 and 57 may be stitched throughout their entire length to the front panel 50, thereby forming a front tubular waistband section throughout their entire length.

Within the rear end of the tubular casing 58, there is inserted the front end of a rear elastic element 59 which is secured therein by stitching 60.

In Figures 10, 11 and 12, a rear waistband portion generally indicated at 61 in the form of a curtain is secured as by stitching to the upper edges of the rear panel 51 and the flap portion 51a, while its lower edge is unsecured except in the vicinity of the side pocket. This rear waist-

band 61 is in the form of a curtain and, as shown in Figures 10 and 12, is made up of three sectional pieces 62, 63 and 64, which overlie each other at their respective adjacent end portions. This curtain 61 can be fabricated as a single piece of material. The lower edge of the curtain 61 is doubled over on itself and secured by a stitching indicated at 65.

Where the curtain portions 62 and 63 overlie each other there is inserted therebetween the rear end of the rear elastic element 59 and the stitching indicated at 66 secures together those overlying parts and the end of the elastic element. In Figure 11, the section of curtain 63 is shown attached at its upper edge to the rear hip portion 51. The rear elastic element 59 is shown lying between the curtain 63 and the rear hip portion.

The curtain section 64 forms with the flap portion 51a, over which it lies, a tubular casing generally indicated at 67 in Figures 10 and 12. Within this tubular element is inserted a forward elastic element 68 which has its rear end secured between the overlying sections 63 and 64 of the waistband as by stitching 69 passing through the overlying sections and the elastic element. The forward end of the elastic element is secured between the overlying facing portions 56 and 57, above described, as by stitching 70, passing through the overlying facing and the elastic element. The forward elastic element 68 is free to move within the tubular casing generally indicated at 67.

In Figure 13, there is shown a modified way of attaching the elastic elements to their waistband portions. In this illustration, the attachment of the forward end of forward elastic element 67' is shown. The curtain or waistband is generally indicated at 61' and comprises a single strip as contrasted with the sectionally built-up curtain 61 shown in Figures 10 and 12. The curtain 61' has formed therein a plait 71 by merely folding a portion of the material of 61' back over itself. Within the plait 71, there is inserted the end of the elastic element 67' and stitching 72 passes through the plait and the elastic element. This same type of waistband construction can be utilized for attaching the rear ends of the elastic elements.

In the modified form of waistband construction shown in Figures 8 through 12, the side swing pocket generally indicated at 73 is of the same construction as described above for the garment illustrated in Figures 1 through 7. The side pocket 73 which is of normal proportions and construction comprises an outer wall 74 and an inner wall 75 which are joined together at their forward edges to form an open plait or foldable portion as indicated at 76. In its most forward position, the forward edge of the plait is indicated at 77 in Figures 8 and 10 while in its most rearward position, the forward edge of the plait is indicated at 77' in Figures 9 and 12. The rearward portion of the upper edge 78 of the outer wall 74, see Figure 12, is attached to the lower and adjacent edge of the front waistband 57 leaving the forward portion of the upper edge of the outer wall unsecured so as to form a portion of the open plait 76. The rear edge of the outer wall 74 is stitched to the rear edge or welt 55' of the front panel 50, see Figure 9. The inner wall 75 whose rear portion lies behind the flap portion 51a has the rearward portion of its upper edge 79, see Figures 10 and 12, stitched to the lower adjacent edge of the forward end of

the rear waistband 61. The rear edge of the inner wall 75 is secured to the forward portion of the rear panel 51 by the seam at 52. The lower portions of the side walls 74 and 75 of the pocket are joined together at their rear and lower edges similar to the corresponding walls in the pocket 34 as at 13a in Figure 1. This joint is below the pocket opening and the seam 52, see Figure 8, and allows the pocket 73 to swing free as a side swing pocket. The forward edge 53 of the flap portion 51a is secured, as described previously, to the adjacent portion of the inner pocket wall 75 by stitching 53'.

It can readily be seen that this modified form 15 of waistband permits the elimination of the use of a belt and the customary belt loops and tunnel loops. It also conceals the elastic elements inside tubular and tubular like casings of the waistband which permits the elastic elements to 20 be out of contact with the shirt or waist garment usually worn by the wearer. The elastic elements work against or in opposition to each other in holding the various parts of the form-fitting garment about the waist of the wearer so as to permit automatic adjustment to the waist of the wearer, and at the same time, effect a smooth, even appearance.

The original and modified forms of waistband above described may be fabricated as a unit 30 and attached to the inside waist portion of a conventional pair of trousers. It may also be fabricated as a unit comprising the waistband and attached pockets for attachment to the inside waist portion of a conventional pair of trousers.

It will be understood that the invention is not limited to the illustrated details of construction but that variations in the form and arrangement of parts are contemplated under the claims which 40 follow.

I claim:

1. A waistband garment of the character described comprising, in combination, a rear panel, a front panel having the rear portion thereof 45 overlying the forward portion of said rear panel and forming an open plait therewith, a rear waist tunnel belt loop attached to the upper edge of said rear panel, a rear waist tubular portion attached to the upper edge of said rear panel behind said rear waist tunnel belt loop and extending forwardly in spaced relationship to the top edge of said front panel, a front waist tubular portion attached to the upper edge of said front panel and being positioned outward of and parallel to the forwardly extending portion of said rear waist tubular portion and having a rearwardly extending portion thereof which has sliding engagement into said rear waist tunnel belt loop, a forward elastic element extending into 55 the forward end of said rear waist tubular portion and having its front end attached to said front waist tubular portion and its rear end attached to said rear waist tubular portion, and a rear elastic element extending within said rear waist tunnel belt loop having its front end attached to the end of the rearwardly extending portion of said front waist tubular portion and its rear end attached to said rear waist tubular portion, said elastic elements being movable in 60 opposite directions for automatically adjusting the waistband to fit the waist of the wearer.

2. A garment of the character described comprising, in combination, a rear panel, a front panel having the rear portion thereof overlying the forward portion of said rear panel and form-

ing a pocket opening therewith, a rear waist tunnel belt loop attached to the upper edge of said rear panel, a rear waist tubular portion attached to the upper edge of said rear panel behind said rear waist tunnel belt loop and extending forwardly in spaced relationship to the top edge of said front panel, a front waist tubular portion attached to the upper edge of said front panel and being positioned outwardly of and parallel to the forwardly extending portion of said rear waist tubular portion and having a rearwardly extending portion thereof which has sliding engagement into said rear waist tunnel belt loop, a forward elastic element extending into the forward end of said rear waist tubular portion and having its front end attached to said front waist tubular portion and its rear end attached to said rear waist tubular portion, a rear elastic element extending within said rear waist tunnel belt loop having its front end attached to the end of the rearwardly extending portion of said front waist tubular portion and its rear end attached to said rear waist tubular portion, and a side pocket for each side of the garment having an inner and an outer wall, said inner wall having the upper portion of its rear edge attached to the forwardly extending portion of said rear panel and the rear portion of its top edge attached to the forwardly extending portion of said rear waist tubular portion thereby leaving the forward unattached portion to form an open plait with said outer wall, said outer wall of the pocket having the upper portion of its rear edge attached to the rear edge of said front panel and the rear portion of its top edge attached to the forward unattached portion to form said open plait with said forward unattached portion of the inner wall of the pocket.

3. An adjustable waistband comprising a rear waist tubular portion, a tunnel belt loop extending adjacently parallel and attached to said rear waist tubular portion, a front waist tubular portion overlying the forward end of said rear waist tubular portion and having a rearwardly extending portion which has sliding engagement into said rear waist tunnel belt loop, a forward elastic element extending into the forward end of said rear waist tubular portion and having its forward end attached to said front waist tubular portion and its rear end attached to said rear waist tubular portion, and a rear elastic element extending within said rear waist tunnel belt loop and having its front end attached to the end of the rearwardly extending portion of said front waist tubular portion and its rear end attached to said rear waist tubular portion, said elastic elements being longitudinally displaceable in opposite directions whereby the rear and front waist tubular portions are automatically adjust-

able relative to each other about the waist of the wearer.

4. A pair of trousers comprising front and rear panels extending into leg portions, said rear panel having a forward extending flap lying underneath said front panel and forming therewith a side pocket opening, a rear waist tubular portion attached to said rear panel, a front waist tubular portion attached to said front panel, a rear waist tunnel belt loop attached to the upper portion of said rear panel, a forward elastic element having its front end attached to said front waist tubular portion and its rear end attached to said rear waist tubular portion, and a rear elastic element extending within said rear waist tunnel belt loop and having its front end attached to said front waist tubular portion and its rear end attached to said rear waist tubular portion, and a side pocket for each side of the trousers having an inner and an outer wall, said inner wall having the upper portion of its rear edge attached to the forwardly extending portion of said rear panel and the rear portion of its top edge attached to the adjacent portion of said rear panel flap portion, thereby leaving the forward unattached portion to form an open plait with said outer wall, said outer wall of the pocket having the upper portion of its rear edge attached to the rear edge of said front panel and the rear portion of its top edge attached to the upper portion of said front panel, thereby leaving the forward unattached portion to form said open plait with said forward unattached portion of the inner wall of the pocket.

RALPH R. FANNING.
